UNITED STATES PATENT OFFICE.

GASTON A. BRONDER, OF NEW YORK, N. Y.

GAS-RETORT-DISCHARGING APPARATUS.

SPECIFICATION forming part of Letters Patent No. 447,022, dated February 24, 1891.

Application filed March 6, 1890. Serial No. 342,870. (No model.)

To all whom it may concern:

Be it known that I, GASTON A. BRONDER, of New York, in the county and State of New York, have invented a certain new and useful Improvement in Gas-Retort-Discharging Apparatus, of which the following is a specification.

My improvement relates to apparatus by which coke and residual products remaining in gas-retorts after the destructive distillation of coal therein has been completed may be removed.

I will describe an apparatus embodying my improvement in detail, and then point out the novel features in claims.

In the accompanying drawings, Figure 1 is a side elevation of apparatus embodying my improvement and showing three retorts in vertical section. Fig. 2 is a side view, on an enlarged scale, of one of a number of rakes employed. Fig. 3 is a top view of the same. Fig. 4 is a view on a larger scale of one of the rake-heads, looking from the inside of the same. Fig. 5 is a view on a scale similar to Fig. 4 of another of the rake-heads, looking from the outside of the same. Fig. 6 is a detail view, on substantially the same scale as Figs. 4 and 5, of guides for the rakes. Fig. 7 is a view on a similar scale looking from the side.

Similar letters of reference designate corresponding parts in all the figures.

A designates a truck supported upon wheels a, which travel upon tracks a', extending along in front of a bank of retorts B. The truck may be moved along into any desired position in front of the retorts. The truck comprises a base-piece A', uprights A² A³, extending from the base A' at the ends of the truck, and connecting-bars a², extending between the end uprights A² A³. The upper of the cross-bars a² constitute rails upon which a carriage C is supported and guided and upon which said carriage may be moved along. I have shown a brace-rod a³ at the upper part of the truck, connecting the uprights A².

The carriage C comprises a frame c, upon which are mounted wheels c', which travel upon the rails a². Secured to one side of the frame c is an upright c², extending from the inner sides of which are pins or projections c³. Extending from one side of the rear upright A² are pins or projections c⁴.

At the forward end of the truck is a slider-

bar D, adapted to be moved vertically in 55 guideways d upon the forward upright A³. Secured upon the slider-bar D are pairs of rollers d'. (Shown more clearly in Figs. 6 and 7.) These rollers are loosely mounted upon stub-shafts d², which are secured in the slider-bar D. The slider-bar D at points intermediate of the rollers d' is provided with inwardly-extending projections d³.

Hung upon the upper of the stub-shafts d² with each pair of rollers is a swinging retaining device D'. Each of these retaining devices near its lower end is provided with a notch d⁴. The retaining devices may be swung into such position that the notches d⁴ will embrace the lower of the stub-shafts d² of 70 each pair outside the lower roller d'. It may be locked in such position by a nut d⁵ upon the screw-threaded outer end of the stub-shaft d². About midway in its length each of said securing devices is provided upon its 75 inner side with a projection d⁶, which, when the retaining device is swung downwardly into the position just described, will be opposite the projection d³ upon the slider-bar D. The rollers d' and the projections d³ d⁶ act as 80 guides to prevent vertical or lateral displacement of rakes E E', which pass between them.

I have shown three pairs of the rakes E E'; but I may use any desired number. These pairs of rakes are each adapted to be moved 85 forward and backward, either separately or together, by the carriage C when the latter is moved by any suitable means. (Not shown in the drawings.) The rake E of each pair is mounted upon its complementary rake E', and is capable of being longitudinally moved thereon, so as to lengthen or contract the length of the rake as a whole. Each pair of rakes therefore constitutes in effect an extensible and contractible rake. It has been 95 found advantageous to make the rake thus extensible and contractible in order that a longer rake having a greater reach into the retorts may be used within a limited space than would otherwise be possible. The handles of each of the rakes is made of comparatively narrow metallic bars. The rakes E' are provided with heads e, shown as of substantially oval shape. The rakes E are provided with substantially oval-shaped heads e'. 105 The handles of the rakes E extend through suitable apertures e², formed in the head e of the rakes E', and are provided with upward-

ly-extending projections e^3 , which prevent a too-extended forward movement of the rakes E upon the rakes E'.

Upon the rear ends of the rakes E are pivoted swinging arms F, which may be swung around into line with the handles of the rakes or into position at right angles thereto, as shown at Figs. 2 and 3. When the rakes E have been moved into their most forward position on the rakes E', the arms F are swung around into line with the handles of the rakes, and should the rakes be connected to the carriage C, so as to move therewith, projections f , with which the upper sides of the arms are provided, will contact with projections f' , extending from the frame c of the carriage C, and will thus prevent rearward longitudinal movement of the rakes E upon the rakes E'. Thus when the rakes have been extended the heads $e e'$ will be maintained in proper position relatively to each other. Each of the rakes E is provided near its rear end and upon its under side with a notch e^4 . These notches are adapted to be passed over the pins or projections c^3 upon the upright c^2 of the carriage C when it is desired to secure the rakes to the carriage, so that they will be moved thereby. When it is not desired to move the rakes with the carriage, they are lifted off from the pins c^3 and are engaged with the pins c^4 upon the uprights A^2 .

Extending from the sides of the rakes E' are pins or projections e^5 , which, when the rakes are engaged with the carriage, will contact with the upright c^2 and act as stops to prevent independent forward movement being imparted to the rakes E E' while in operation, or, in other words, which will cause the rakes to be drawn rearwardly by the carriage during this rearward movement.

It being desired to operate one or more of the extensible rakes, the rake or rakes E are moved forward into their farthest position upon the rake or rakes E'. The latter are then secured to the carriage as desired, the arms F being swung around into line with the rakes E. The carriage is then moved forward, so as to carry the rakes into the retorts. When the rake-heads $e e'$ have reached the rear of the retorts, they will drop downwardly at or near the rear of the material therein, and the returning movement of the carriage will cause a portion of such material to be raked from the retorts. Such material as is not raked out by the head e will be raked out by the head e' , and a few to-and-fro movements of the carriage C will suffice to thoroughly empty the retorts.

The vertical movement of the rakes which is necessary to permit them to pass over the top of the charge in the forward movement and to drop down behind the charge previous to the return is effected by the movement of the slider-bar D in the ways d. This movement is produced in the usual manner. The weight of the slider-bar and the rakes is counterbalanced by a weight g upon a lever g' ,

connected by means of a link g^2 to the upper end of the slider-bar.

In Fig. 1 I have shown in dotted lines the position which the rollers d' may occupy when in a lowered position. The rakes may be easily placed upon or removed from the truck by swinging the retaining devices D' around sufficiently to admit of this. 75

What I claim as my invention, and desire to secure by Letters Patent, is—

1. In apparatus for discharging gas-retorts, the combination, with a track, of a carriage mounted on the track and an extensible and contractible rake having a removable engagement with the carriage for moving it forward and backward with the carriage or not, at pleasure, substantially as set forth. 80

2. In apparatus for discharging gas-retorts, the combination, with a track, of a carriage mounted on the track and an extensible and contractible rake composed of two parts, each provided with a rake-head, one of the parts having a longitudinally-sliding engagement 90 with the other part, said parts being controlled in their movements by the movement of the carriage, substantially as set forth. 85

3. In apparatus for discharging gas-retorts, the combination, with a track, of a carriage mounted on the track, an extensible and contractible rake composed of two rake-sections, one of the sections having a longitudinally-sliding movement upon the other section, the rake having a removable connection with the carriage, and stops located in position to engage one of the rake-sections and limit its longitudinal movement relatively to the other section, substantially as set forth. 95

4. In apparatus for discharging gas-retorts, the combination, with a track, of a carriage mounted thereon, an extensible and contractible rake having a removable connection with the carriage and consisting of two rake-sections, one of the sections having a limited longitudinally-sliding movement relatively to the other section, and a swinging arm upon one of the rake-sections for causing it to be slid upon the other section, substantially as set forth. 105

5. In apparatus for discharging gas-retorts, the combination, with a track and a carriage mounted thereon, of a reciprocating rake under the control of the carriage and a guide for directing the rake, said guide consisting of a pair of rollers in position to engage the opposite sides of the rake-handles, a permanent guide-bar in position to prevent the rake from displacement at one side between the rollers, a swinging bar having a movement 110 into and out of position to keep the rake from displacement at the opposite side between the rollers, and means for locking the swinging bar in position, substantially as set forth. 115
